6 SHEETS—SHEET 6,

UNITED STATES PATENT OFFICE.

ADOLPH K. MALMQUIST, OF SOUTH BELLINGHAM, WASHINGTON, ASSIGNOR TO PERFECT VACUUM CANNING COMPANY, OF SOUTH BELLINGHAM, WASHINGTON.

CAN-CAPPING MACHINE.

1,241,233.

Specification of Letters Patent. Patented Sept. 25, 1917.

Application filed March 4, 1916. Serial No. 82,161.

To all whom it may concern:

Be it known that I, ADOLPH K. MALMQUIST, a citizen of the United States, and a resident of South Bellingham, in the county 5 of Bellingham and State of Washington, have invented certain new and useful Improvements in Can-Capping Machines; and I do hereby declare the following to be a full, clear, and exact description of the invention, such as will enable others skilled 10 in the art to which it appertains to make and use the same.

This invention relates to improvements in can capping machines, one object of the 15 invention being to provide means whereby a cap may be seamed to a can body in two successive operations in vacuous chambers, and to so construct and arrange the mechanism that a vacuous condition may be maintained in the two chambers during both 20 seaming operations and so that the exhausting means for one chamber shall not interfere with the exhausting means for the other chamber.

25 A further object is to provide simple and efficient seaming mechanisms, and means which shall operate automatically to operate and control the seaming mechanisms.

30 A further object is to provide simple means for preventing the discharge of a cap when a can is not in place to receive it.

35 A further object is to provide cap releasing means which shall be controlled by the movement of a can body to the can carrier.

40 A further object is to provide means which shall operate to prevent the operation of the seaming mechanism when no can is in place in the carrier.

45 A further object is to so construct the apparatus that the operating parts may be readily accessible for repairs without disconnecting the parts.

50 A further object is to construct the apparatus in such manner as to facilitate and insure adequate lubrication.

55 A further object is to provide simple and efficient can discharging means.

60 A further object is to provide an efficient guiding means for a can within the sealing 50 chambers.

With these and other objects in view the invention consists in certain novel features of construction and combinations of parts as hereinafter set forth and pointed out in 55 the claims.

In the accompanying drawings; Figure 1 is plan view of a machine embodying my improvements; Fig. 2 is a vertical transverse sectional view on the line 2—2 of Fig. 1; Fig. 3 is a horizontal sectional view on the line 3—3 of Fig. 2; Fig. 4 is a horizontal sectional view on the line 4—4 of Fig. 2; Fig. 5 is an enlarged plan view of the revolute can carrier; Fig. 6 is a sectional view on the line 6—6 of Fig. 5; Figs. 7 and 8 are enlarged vertical and horizontal views through the pockets or chambers of the can carrier; Fig. 9 is a bottom plan view illustrating the seaming mechanism; Fig. 10 is a vertical transverse section on the line 10—10 of Fig. 9; Fig. 11 is a view in section on the line 11—11 of Fig. 9; Fig. 12 is a view in section (and partly in elevation) on the line 12—12 of Fig. 9; Fig. 13 is a detail view of one of the levers of the seaming mechanism; Fig. 14 is a fragmentary view partly in section showing parts of the cap feeding and can discharging means; Fig. 15 is an enlarged detail view illustrating the cap magazine and the manner of discharging caps therefrom; Fig. 16 is a detail view of the cap ejector; Figs. 17 and 18 are enlarged detail views of the can seat 93 and the guide 88 respectively; Figs. 19 and 20 are plan and sectional views respectively, showing the cap magazine; Fig. 21 illustrates the coupling between the rod sections 158—160; Fig. 22 is a detail view showing the cam 169; Fig. 23 is an enlarged plan view (partly in section) of one of the seaming heads; Fig. 24 is a fragmentary sectional view illustrating the manner in which a can is discharged, and Fig. 25 is an enlarged detail view showing the adjusting means at the upper end of the rod 114.

1 represents a base plate supported on suitable legs 2,—said base plate constituting the bottom of a casing 3 and plate 4 constitutes the top of said casing. The bottom and top plates 1—4 are made flaring (as shown in Figs. 3 and 4) for about one-half the length of each so that the casing may properly accommodate the gearing disposed therein, and the edges of the respective plates are connected by vertical side walls 5. The respective ends of the casing 3 are closed by end plates 6 and 7, and thus said casing forms a closed chamber in which the major portion of the driving gearing is located and immersed in oil contained in said chamber.

Oil may be supplied to the casing through a pipe or nipple 8 communicating with the upper portion thereof, and a drain cock 9 may be provided at the bottom of the casing, as shown in Fig. 1. The respective end plates 6, 7 of the casing are provided with bearings 10—11 for a main driving shaft 12, the latter extending beyond its bearing at 10 and provided with a pulley 13 to receive power from any suitable source. The bottom 1 of the casing is provided with an upward enlargement 14 which may form an intermediate bearing for the driving shaft, and near the central portion of the casing, 15 bearings 15—16 are provided for the inner ends of shafts 17—18 disposed at an acute angle,—the outer ends of said shafts being mounted in bearings 19—20 formed on the end plate 7 of the gear casing 3. A large 20 beveled gear 21 is secured to the main driving shaft 12 and transmits motion to gears 22—23 on the shafts 17—18 and serving to drive said shafts in reverse directions.

An upper frame plate 24 is located a sufficient distance above the upper plate 4 of the casing to accommodate a revoluble can carrier 25 between said plates, and so that said carrier may have close-fitting contact with both of said plates. The upper frame 30 plate 24 is provided with arms 26 to receive the shanks of posts 27 rising from arms 27^a on the gear casing and by means of which said upper frame plate is supported. The shanks of the posts 27 pass freely through 35 holes in the arms 26 and their upper portions are threaded for the reception of nuts 28, while that portion of each post adjacent to the shank is somewhat contracted and threaded for the reception of an annular nut 40 or sleeve 29. The nuts or sleeves 29 bear at their upper ends against the under faces of the arms 26, so that by adjusting said nuts or sleeves, the upper frame plate 24 may be adjusted to insure proper close contact with 45 the upper face of the revoluble carrier.

The upper frame plate 24 is provided with an upwardly-projecting tubular enlargement 30 constituting a bearing for a vertical shaft 31, the lower end of which 50 passes through the upper plate 4 of the gear casing 3 and is supported in a socket in the upper portion of the enlargement 14, within which socket, a thrust bearing 32 for said shaft is located. The upper 55 end of the shaft 31 projects above the tubular enlargement 30 and has a bearing in a boss 33 formed at the free end of a bracket 34 secured to the upper frame plate 24. Between the bracket 34 and the upper end of 60 the tubular enlargement 30, a large gear wheel 35 is secured to the shaft 31 (for a purpose hereinafter explained) and to the lower portion of said shaft, a bevel gear 36 is secured and receives motion from a bevel gear 37 secured to the main driving shaft 65

12. The upper casing plate 4 is made with a depending guide bearing 38 for a sleeve 39 mounted loosely on the shaft 31 and extending upwardly through the axial portion of the revoluble can carrier 25, to which latter, said sleeve is keyed. For reasons which will be hereinafter made apparent, it is necessary that the can carrier shall have a step-by-step movement imparted to it, and to accomplish this, the gearing now to be described may be employed: A disk or Geneva wheel 40 is secured to the lower end of the tubular shaft or sleeve 39 and made with a plurality of slots 41, thus forming a corresponding number of arms 42,—each of 80 which latter is made with a curved recess 43 in its free end. A vertical shaft 44 is mounted in bearings 45—46 in the gear casing and carries a gear wheel 47 and a cam block 48,—the latter to turn freely in the 85 curved recesses 43 of the disk 40. The gear wheel 47 carries a roller pin 49 to enter the slots 41 of the disk 40, and thus cause said disk and the can carrier with which it is connected through the tubular shaft 39, to 90 be turned step-by-step during the rotation of the gear wheel 47, as will be readily understood. The gear wheel 47 is continuously rotated by a gear 50 which may be formed integral with the gear 36 on the vertical shaft 31.

Two seaming heads 51—52 are secured, side by side, upon the top frame plate 24, and the latter is recessed to increase the depth of the chamber 53 within each seaming head and also to decrease the thickness of those portions of the frame plate 24 which form the bottoms of the seaming head chambers. The rotary can carrier 25 is made with an annular series of pockets 54 (six 105 such pockets being shown in the drawing) open at the periphery of the carrier and when two of these pockets become disposed under the two seaming heads, they become portions of sealing chambers communicating 110 through openings 55 in plate 24 with the chambers 53 within the seaming heads (which also form parts of the sealing chambers) and when two pockets of the can carrier thus form parts of sealing chambers, 115 their normally open outer or can-entering ends will be closed air-tight by means of a curved cover plate 56 disposed between the frame plates 4 and 24. This cover plate is secured to the plates 4—24 by means of 120 screws passing through elongated slots 57 in lugs on said cover plate, so that the latter may be adjusted to closely engage the peripheral portion of the can carrier. Such adjustment may be effected and the cover 125 plate secured in position, by means of adjusting screw 58 passing through arms 59 secured to one of the posts 27, and engaging in sockets in said cover plate.

The sealing chamber formed as above de- 130

scribed will be exhausted during the sealing of a cap to a can, by means which will be hereinafter fully explained.

At a point removed a distance from the center of the seaming head 51 equal to the distance between the centers of two adjacent pockets in the can carrier, the upper frame plate is formed with flanges 60 on which the base 61 of a cap magazine 62 is secured. The 10 caps 62^a are normally supported in the magazine by means of a blade 63 mounted to slide in a dovetail groove in the bottom of the magazine base 61.

A table 64 is supported by two of the 15 posts in proximity to the cap magazine and over this table, a can chute 65 passes for guiding cans to the pockets of the can carrier. A sprocket wheel 66 is secured to a vertical shaft 67 which passes through a bearing 20 sleeve 68 depending from the table 64. A sprocket conveyer chain 69 passes over the sprocket wheel 66 and over another sprocket wheel (not shown) at the receiving end of the guiding chute. The conveyer chain is 25 provided with arms 70 which project over the guiding chute for moving the cans forwardly, and these arms are so spaced apart that, during the travel of the chain, a can will be fed to the can carrier 25 upon the 30 arrival of one of the pockets thereof under the cap magazine, the gearing which drives said can carrier 25 and conveyer chain being properly timed to accomplish this result. To provide driving means for the conveyer 35 chain 69, a sprocket wheel 71 is secured to the lower end of the vertical shaft 67 and receives motion, by means of a sprocket chain 72 from a sprocket wheel 73, all of said sprocket wheels 66, 71 and 73 being of the 40 same size. The sprocket wheel 73 is secured to one end of a shaft 74 and to the other end of said shaft, a bevel gear 75 is secured. This bevel gear receives motion from another bevel gear 76 carried by a shaft 77 and secured to the same shaft 77 is a comparatively 45 large sprocket wheel 78 to which motion is imparted by a chain 79 from a small sprocket wheel 80 secured to the main driving shaft 12 in proximity to the pulley 13 thereon.

50 A curved lever 81 is pivotally connected at one end (as at 82) over the table 64 and projects partly over the discharge end of the guide chute 65, the free end of said lever being formed with an L-shaped arm 83 55 which projects forwardly at one side of the cap magazine and is provided near its free end with a slot 84 to receive a pin 85 carried by the cap discharging blade.

When a can is caused, by an arm 70 on 60 the conveyer chain 69, to approach a pocket of the rotary can carrier, said can will engage the lever 81 and so move the same as to cause the blade 63 to be withdrawn from under the bottom cap in the magazine 62. When 65 the can shall have entered the pocket in the

can carrier so as to be disposed under the cap magazine, a cam 86 on the shaft 67 will engage the lever 81 and so move the same as to cause the blade 63 to enter between the two bottom caps in the magazine and force 70 the lowermost cap to be discharged and to rest upon an annular countersunk shoulder 87 at the top of the pocket 54 in the can carrier 25, ready to be subsequently applied and double seamed to the can body. 75

From the above description, it will be readily seen that as the discharge of a can cap is directly controlled by the movement of a can body, no cap can be released from the magazine unless a can body has entered 80 a pocket of the can carrier 25 to receive it.

Within each pocket or sealing chamber of the rotary carrier 25, a partly circular guide 88 is loosely disposed so that it may be vertically movable, said guide having an 85 open mouth portion 89 (Fig. 18) to receive and assist in directing the can into the pocket or sealing chamber. Normally, the guides 88 rest upon disks or plates 90 screwed into the bottoms of the pockets or 90 sealing chambers, each of said disks or plates being made with a hole 91 for a purpose hereinafter explained.

Each guide 88 is made in its inner face with a recess 92 for the accommodation of 95 a can seat 93, the latter being provided with a depending boss 94 which enters the hole 91 in the plate 90. The recess 92 is of sufficient depth to permit limited upward movement of the can seat, and the shoulder 95 100 formed by the upper end of said recess constitutes an abutment for the bottom flange 96 of a can 97 resting upon said can seat. The guide 88 is normally pressed downwardly by means of springs 98 which rest 105 at their lower ends in sockets in said guide and at their upper ends, said springs engage depending pins 99. The upper portion of each pocket or sealing chamber is somewhat enlarged, as at 100, to accommodate the 110 flange 101 at the upper end of the can 97.

The mechanisms operated from the two shafts 17-18 for manipulating the cans in the sealing chambers and for operating and controlling the respective sealing mechanisms, are the same in construction and hence a detail description of one set of such mechanisms will suffice for both. 115

Each seaming head is provided centrally with an upwardly projecting tubular extension 102, and the latter is provided with an upwardly projecting yoke 103 formed in its top member with a vertical hole 104, said yoke being also provided at its upper end with a laterally projecting L-shaped 125 arm 105.

A seaming-roll carrier 106 is located within the chamber of each seaming head and is provided with a tubular spindle 107 projecting upwardly through the tubular 130

extension 102 on the seaming head, and formed with a shoulder 108 to engage the under face of the top wall of said seaming head. A gear 109 is keyed to the upper portion of the tubular spindle 107 and receives motion from the large gear 35 on the vertical shaft 31.

A tubular shaft 110 is located within the tubular spindle 107 of the seaming roll carrier and is provided at its lower end within the seaming head chamber, with a chuck 111. The tubular shaft 110 is threaded at its upper end and passes through the hole 104 in the yoke 103, to which latter it is secured against rotation by means of a key 112. Nuts 113 are located on the threaded upper portion of the tubular shaft 110 and bear, respectively against the upper and lower faces of the top of the yoke 103. By connecting the chuck shaft with the yoke 103 as above described, the chuck will be prevented from turning but it may be readily adjusted vertically.

A rod 114 passes freely through the tubular shaft 110 and is provided at its lower end with a knock-out head 115 disposed under the chuck 111 and adapted to engage and to be pressed downwardly upon a can cover. The knock-out head in the second sealing head will preferably be provided with suitable projections to form a letter, figure or other character, whereby said knock-out head will also constitute a marker for the can caps or covers, to indicate either the contents of the cans or other desired information. The rod of the knock-out heads may be adjusted for length by means of a collar 116 screwed on the upper end of said rod and held from turning by means of a set screw 117.

Each seaming-roll carrier 106 is made with two bifurcated arms 118, in which levers 119 are pivotally supported between their ends, by means of pivot pins 120 and each of such pivotal mountings may be provided with a lubricating device 121. At one end of each lever 119, a seaming roll 122 is mounted and suitable lubricating means 123 may be provided for each seaming roll. It will be understood that the seaming rolls in the first seaming head are so formed as to form an interlocking double seam between a cap and can body and that the seaming rolls in the second seaming head will be so formed as to complete the double seam so as to hermetically seal the cap to the cover. The formation of the respective pairs of seaming rolls for accomplishing such double seaming is well known in the art and need not be specifically explained herein.

Each seaming-roll lever 119 is provided near the end thereof opposite to that at which the seaming roll is mounted, with a pivoted, spring trip-arm 124, which is connected, between its ends, with the lever by

means of a screw 125, said screw serving to hold the spring arm against an adjusting screw 126 carried by the lever. The bent end of each spring arm 124 is provided with a finger 127 to engage a cone 128 mounted to slide vertically on a portion of the tubular spindle 107 within the seaming head and near the carrier 106 at the lower end of said spindle. The cone 128 may be provided with a lubricating device 129. The fingers 127 on the spring arms 124 are maintained in engagement with said cone by means of springs 130, each of which is attached at one end to one of the levers 119 and at the other end to the carrier 106. Each lever 119 is provided at the end thereof which carries the seaming roll, with a limiting screw 131 to engage the chuck, whereby the pressure of the seaming rolls against the cap and can flanges to be seamed may be regulated.

When a can body and a cap shall have been fed to the rotary can carrier as previously explained, the can carrier will be turned by the operation of the step-by-step gearing hereinbefore described, so that the pocket or sealing chamber of the carrier 25 containing the can body and cap will become disposed under the first sealing head; at which time the mouth of the pocket or sealing chamber will become sealed by the curved cover plate 95 56. A rod 132 passing through said cover plate will now operate to press the can body properly in position in the guide 88. To provide means for thus operating the rod 132, a bell-crank-lever 133 is pivotally supported in the upper portion of the gear casing and having one of its arms projecting through an opening in the top plate 4, said upwardly projecting arm of the bell-crank-lever being provided with a spring-pressed pivoted arm 134 connected with the push rod 132. The other arm of the bell-crank 133 is connected with the upper end of a rod 135,—the latter passing freely through a vertical guide 136 within the gear casing and provided at its lower end with a roller 137 to engage an actuating cam 138 secured to the shaft 17.

The can is now in position in a sealing chamber of which the seaming head forms a part, and ready to be raised, with its cap to the seaming mechanism. The can and cap will be thus presented to the seaming mechanism by means of the devices now to be described.

A tubular guide 139 depends within the gear casing, from top plate 4 and communicates with a suitable opening in said plate for the passage of a plunger 140 movable through said tubular guide,—the upper end 125 of said plunger being adapted to engage the boss 94 on the can support 93. The plunger 140 is provided at its lower end with a roller 141 to engage a cam 142 on the shaft 17, whereby said plunger will be moved verti- 130

cally to raise the can support and can body with its cover to the seaming mechanism. In order that the plunger 140 may accommodate itself to cans which may vary some-
5 what in height, said plunger is made in tele-
scoping sections 143—144, the relative move-
ments of which are limited by a pin-and-
slot construction illustrated at 145. A spring
146 is located within the tubular member 144
10 of the plunger 140 and bears at its lower end
upon the upper end of the member 143—the
upper end of said spring bearing against a
follower 147 located within said tubular
member. The follower is provided with a
15 threaded shank 148 passing through a
threaded hole in the upper end of the
plunger member 143 and is held at any de-
sired adjustment by means of a set screw
149. It is apparent that the tension of the
20 spring may be adjusted by adjusting the
follower through the medium of its threaded
shank.

As the plunger 140 is raised by the action
25 of the cam 142, its upper end will engage the
boss 94 on the can seat 93 and thus raise the
can. As the can rises its bottom flange will
engage the shoulder 95 of the spring-pressed
guide 88 and raise the latter, the pressure
30 of the guide upon the lower flange of the can
serving to hold the latter from turning dur-
ing the subsequent seaming operation. Dur-
ing the ascent of the can, its upper end will
engage the can cap and raise the same from
35 its seat, and finally said cap and the upper
flanged end of the can will be presented to
the chuck 111 ready for the first seaming
operation, the cover being held in place by
engagement with a spring-pressed knock-
40 out device 115 hereinafter more particularly
described.

The seaming roll carrier 106 will be con-
tinuously rotated by the operation of the
gears 35 and 109, but prior to the presenta-
45 tion of the can and cap to the seaming chuck,
the seaming rolls are not disposed to opera-
tively engage the flanges of the cap and can.
When the can and cap shall have been pre-
sented to the chuck as above explained, the
50 mechanism for bringing the seaming rolls
into operative relation to the cap and can
for seaming the former to the can will be
brought into action. These devices will
now be explained.

The seaming head 51 (and also the seam-
55 ing head 52) is made with an enlargement
150, in which one end of a lever 151 is piv-
otally supported, said lever being thus lo-
cated within the seaming head. The other
60 end of the lever 151 is bifurcated and made
to embrace the cone 128, with which the
same is pivotally connected. A link 152
passes through the top of the seaming head
(suitable packing being provided for said
65 link) and is connected at its upper end with
one arm of a lever 153 pivotally mounted

between its ends at the upper end of a post
154 rising from the seaming head. In order
that the connection between the lever 153
and the cone-shifting lever 151 shall be ad-
justable, said link is made in two parts con-
70 nected by a turn-buckle 155. A spring 156
is attached to the outer arm of the lever 153
and to a pin 157 projecting from the seam-
ing head,—said spring serving to retain the
cone normally in and return it to its ele-
75 vated position.

The upper end of a rod section 158 is piv-
otally attached to the outer arm of the lever
153, and at its lower end, this rod section is
provided with a head 159 (Fig. 21) to enter
80 a socket near the upper end of a rod section
160 whereby said rod sections 158—160 are
removably coupled together. The lower rod
section passes downwardly through a guide
161 depending within the gear casing and
85 is provided at its lower end with a roller
162 to coöperate with a cam 163 on the shaft
17. It is apparent that the cam 163 will
operate to reciprocate the rod 158—160 and
that when said rod moves upwardly, motion
90 will be imparted, through the lever 153, link
152 and lever 151 to the cone 128, thus caus-
ing the latter to descend and actuate the roll-
carrying levers 119 to bring the seaming
95 rolls into operative relation to the flanges
of the cap and can body to perform the first
operation of double-seaming the cap to the
can. It is also apparent that during the de-
scent of the rod 158—160, motion will be
100 imparted to the cone to raise the same and
thus permit the seaming rolls to be moved
out of operative relation to the can and cap,
by the action of the springs 130.

The lower portion of the rod section 158
above the coupling head 159 is flattened
105 and made with a vertical slot 164 for the
reception of a pin 165 whereby the push rod
132 is connected with said rod section 158.
Should there be no can in a pocket or seal-
ing chamber when the same arrives under a
110 seaming head, the push rod 132 will be
moved (by the operation of the cam 138
and its connections with said push rod) into
the sealing chamber such a distance as to
cause said rod 132 to move the upper rod
115 section 158 laterally and uncouple said rod
section from the rod section 160. When the
rod sections 158—160 are thus disconnected,
motion cannot be imparted to the cone-shift-
ing means, and hence the seaming rolls will
120 not be moved to operative position when
there is no can in the sealing chamber. It
will be apparent from an inspection Fig. 2,
that when a can occupies a sealing chamber
in position to be subjected to the action of
125 the seaming mechanism, the push-rod 132
will be so positioned that the rod sections
158—160 will be held in coupled relation
to each other, so that the seaming-roll con-
trolling cone 128 can be operated.

After the first seaming operation shall have been completed, the descent of the plunger 140 (by the action of the cam 142) will permit the can and applied cap to descend from the seaming head. In order to insure such descent of the can and cap, the knock-out head 115 is provided. The upper end of the rod 114 carrying said head is engaged by one arm of a lever 166. This lever is pivotally supported between its ends by the L-shaped arm 105, and to its other arm, the upper end of a rod 167 is pivotally attached. This rod extends downwardly through a suitable guide 168 in the gear casting and at its lower end, said rod may be engaged by a cam 169 carried by the gear 22 (or 23) on shaft 17 (or 18). A collar 170 is secured to the rod 167 and between this collar and the top plate 4, a spring 171 encircles said rod 167. This spring will cause operation of the rod 167 and lever 166 to depress the knock-out device to cause descent of the capped can from the seaming mechanism and normally retain said knock-out device in its lower position. Should the capped can stick, its descent will be further insured by the actuation of the rod 167 by the cam 169. The operation of the knock-out device by means of the cam 169 at the conclusion of the second seaming operation in the second seaming head 52, will serve to press the knock-out head (in the second seaming head) against the can cap with sufficient force to mark the cap, as previously explained.

Reverting now to the completion of the seaming operation in the first seaming head and the descent of the capped can into the pocket or sealing chamber in the can carrier 25, it will be readily understood that the operation of the step-by-step driving mechanism previously explained, will cause the carrier 25 to turn one step and bring the can with its partially seamed head to position under the second seaming head, where the same operations as those above described will be repeated. When the can carrier 25 begins to turn, the cam 138 will operate to move the rod 135 upwardly, and thus cause the bell-crank 133 to be turned in a direction to withdraw the push rod 132. As the push rod is thus moved backwardly, it will cause the upper rod section 158 to be uncoupled from the rod section 160 and hence the seaming-roll controlling cone cannot then move.

Assuming now that a capped can has been subjected to the completion of the double seaming of the cap in the second seaming head 52 and that the finished can has been lowered within the pocket or sealing chamber of the carrier 25, a movement of another step of said carrier will bring the completely capped can to the discharging position. When this position is reached, the capped

can will be moved out of the pocket of the carrier, by the operation of an ejector-rod 172 (one of such rods being provided for each pocket of the carrier 25), said ejector rod being actuated for this purpose by means of a cam 173 secured upon the top plate 4. The ejector rods are loosely mounted in the rotary carrier 25 and will be pushed back by cans entering the pockets of the carrier during the can feeding operations previously described.

When a capped can is ejected from the carrier 25, it will tip onto an inclined chute 174 (Figs. 1 and 24) and be guided by said chute to a suitable conveyer 175, by which it may be delivered at any desired place.

It is desirable that the seaming operations shall be accomplished in vacuous chambers, and hence provision is made for exhausting the air from the sealing chambers when the cans are in position under the seaming heads, said seaming heads as well as the pockets in the carrier 25 constituting, at such time, parts of the vacuous sealing chambers. The means employed for exhausting said sealing chambers will now be explained.

Curved, elongated ports 176 and 177 are formed in the top casing plate 4, and communicate respectively, with pipes 178—179, said pipes being connected with a suitable double cylinder exhaust pump (not shown). The elongated ports are parallel with each other and are of sufficient length to extend from one can seaming position to the other as shown in Fig. 3.

In the drawing, I have shown the rotary carrier 25 with six pockets to form sealing chambers when disposed under one or the other of the seaming heads. Alternate pockets are provided with air ducts 180 protected by screens or strainers 180^a so disposed as to communicate with the curved port 176 and the other set of alternate pockets are provided with ducts 181 (similarly protected by screens or strainers) arranged to communicate with the curved port 177. With such arrangement, a pocket of carrier 25 forming a sealing chamber with the first seaming head, 51, will communicate with the exhausting port 176 and the pocket 115 will continue to communicate with such exhausting duct 176 while this pocket is traveling from the first seaming head 51 to the second seaming head 52 and while this pocket is under the second seaming head. As the next pocket of the carrier arrives under the seaming head 51 and cooperates therewith to form a sealing chamber, the duct 181 of said next pocket will communicate with the exhausting port 177 and continue in such communication until after the completion of the seaming operation in the second seaming head 52. With such arrangement, there will be no interference between the exhausting of the air in the two 130

adjacent sealing chambers. In other words, there will be no conflict between the exhausting of the chamber containing one can, and the exhausting means for the chamber containing the next can.

5 In order that ready access may be had to the seaming mechanism within the seaming heads without necessity for disconnecting the operating shafts or without removing the seaming heads, each of said seaming heads is made with an opening which is normally closed by means of a plate or door 182.

15 While I have described the machine, as operating to double-seam caps to the upper ends of cans, it will be understood that the machine may also be used to seam the bottoms to cans. It will also be understood that the pivotal connections between the reciprocating rods and the pivoted levers are sufficiently loose to have proper amount of play.

20 Numerous slight changes might be made in the details of construction of my invention without departing from the spirit thereof or limiting its scope and hence I do not wish to restrict myself to the precise details herein set forth.

25 Having fully described my invention what I claim as new and desire to secure by Letters-Patent, is:—

30 1. In a can capping machine, the combination with a seaming head and a can and cap carrier, of seaming devices within the seaming head, means for rotating said seaming devices, a controlling device for said seaming devices located within the seaming head, a lever mounted within the seaming head and connected with said controlling device, a lever mounted exteriorly of the seaming head, a longitudinally adjustable connection between said levers, a cam, means for driving the same, and a connection between said exterior lever and said cam.

35 2. In a can capping machine, the combination with a can and cap carrier and a seaming head, of seaming devices within the seaming head, a controlling device for said seaming devices within the seaming head, a lever mounted within the seaming head and connected with said controlling device, a lever mounted exteriorly of the seaming head, a connection between one arm of said exterior lever and the lever in the seaming head, a cam, a connection between said cam and the other arm of said exterior lever, and a spring connected at one end with said exterior lever and attached at its other end to a fixed part.

40 3. In a can capping machine, the combination with a can and cap carrier, seaming devices, controlling means for the seaming devices, and operating means for said controlling means, of means disposed to engage 65 a can in the carrier and operative to un-

couple said operating means when no can is in the carrier in position under the seaming devices.

4. In a capping machine, the combination with a can and cap carrier, and seaming devices, of controlling means for said seaming devices, and actuating means for said controlling means, and means connected with said actuating means and adapted to enter the carrier and render said actuating means 75 inoperative when no can is in the carrier under the seaming devices.

5. In a can capping machine, the combination with a can and cap carrier, seaming devices, and a controlling device for said seaming devices, of a rod comprising two sections removably connected together, connections between one end of said rod and said controlling device, a cam with which the other end of the rod is connected, a push 80 rod connected with one section of said rod and adapted to enter the carrier, and means for moving said rod into the carrier, whereby the sections of said two part rod will be disconnected and said controlling device 85 rendered inoperative if no can is in position in the carrier to receive said push rod.

6. In a can capping machine, the combination with a can and cap carrier, having pockets to receive cans, seaming devices, a 95 controlling device for said seaming devices, and actuating means for said controlling device, of means for sealing a pocket of said carrier, a push rod passing through said sealing means and adapted to enter a pocket 100 of said carrier and engage a can therein, a connection between the push rod and the actuating means for the controlling device, a bell-crank connected with said push rod, a cam, and a connection between said cam 105 and bell-crank.

7. In a can capping machine, the combination with a can and cap carrier, two sets of seaming mechanisms, and controlling devices therefor, separable actuating means for 110 said controlling devices, rods connected with said separable actuating means and adapted to enter the carrier beneath said seaming mechanisms, and means for moving said rods into and out of the carrier, whereby 115 said actuating means will be separated if no can is in the carrier and also when one or the other rod is withdrawn and the carrier is moving a can from one seaming mechanism 120 to the other or from the second seaming mechanism.

8. In a can capping machine, the combination with a can and cap carrier, seaming mechanism, and a controlling device for said seaming mechanism, of a rod to enter the 125 carrier beneath the seaming mechanism, separable operating means for said controlling device and connected with said rod, a bell-crank, means for oscillating said bell-crank, and a spring pressed arm carried by 130

- said bell-crank and connected with said rod, whereby when the rod is withdrawn from the carrier said actuating means will be disconnected and when no can is in the carrier 5 to receive said rod, said actuating means will be disconnected, and whereby engagement of said rod with a can will maintain the parts of said actuating means in operative relation to each other.
- 10 9. In a can capping machine, the combination with a gear casing adapted to contain lubricant, a superstructure, a can and cap carrier mounted in said superstructure, and two sets of seaming mechanisms also 15 supported by said superstructure, of a main driving shaft in the gear casing, gearing between said shaft and said carrier, two radiating shafts in the gear casing under the respective seaming mechanisms, gears carried 20 by said radiating shafts, a gear secured to the main driving shaft and meshing with the gears on the radiating shafts, gearing between the seaming mechanisms and the main driving shaft, controlling means for 25 the respective seaming mechanisms, cams on the respective radiating shafts, and connecting devices between said cams and the respective controlling means.
- 4 10. In a can capping machine, the combination with a gear casing and a superstructure, of a can carrier mounted in said superstructure, two seaming mechanisms carried by the superstructure, and controlling means 30 for said seaming mechanisms, of a main driving shaft in the gear casing, a vertical shaft, gearing between the vertical shaft and the main shaft, gearing between the vertical shaft and the seaming mechanisms, step-by-step driving means between the main driving 35 shaft and the can carrier, radiating shafts in the gear casing, gearing between the radiating shafts and main driving shaft, and actuating means between said radiating shafts and the controlling means of said 40 seaming mechanisms.
11. In a can capping machine, the combination with a rotary carrier having pockets, seaming mechanism, a main driving shaft, and mechanism actuated from said driving 50 shaft for operating said carrier and seaming mechanism, of a can conveyer, guiding means for directing a can to a pocket of the carrier, a driving shaft for said conveyer, gearing between said shaft and the main 55 driving shaft, a cap magazine over the carrier, a sliding cap discharging plate at the bottom of the magazine, a pivoted lever connected with said sliding plate and having a part disposed in the path of the can over 60 said guiding means whereby said sliding plate will be operated in one direction by the movement of a can entering the carrier, a cam on the conveyer shaft for moving the lever and sliding plate in the reverse direction to discharge a cap onto the carrier over 65 the can therein, and means for subsequently presenting the can and cap to the seaming mechanism.
12. In a can capping machine, the combination with a rotary can and cap carrier 70 having pockets, and a fixed seaming head over the same, said seaming head coöperating with the pockets of the carrier successively to form sealing chambers, a curved plate for closing said sealing chamber, means for adjusting said plate to insure a close fit between the same and the carrier, seaming mechanism in the seaming head, means for feeding cans and caps to the pockets of the carrier successively, and 75 means for raising a can and cap in a sealing chamber and presenting the same to the seaming mechanism.
13. In a can capping machine, the combination with framework, a rotary can and cap carrier having pockets, a fixed seaming head coöperating with the pocket of the carrier successively to form sealing chambers, means for locating a can and cap in each sealing chamber, an adjustable plate 80 for closing such sealing chambers, arms secured to the framework, screws passing through said arms and engaging said plate to retain said plate in fitting contact with the carrier, seaming mechanism in the seaming head, and means for raising a can and cap in a sealing chamber and presenting the same to the 85 seaming mechanism.
14. In a can capping machine, the combination with a rotary can and cap carrier 90 having pockets, and means for feeding cans and caps to the successive pockets of the carrier, of two seaming heads to coöperate with two pockets of the carrier simultaneously to form sealing chambers, means for closing such sealing chambers, means for exhausting the sealing chambers formed by alternate pockets of the carrier with one of the seaming heads, means for separately exhausting the sealing chambers formed by the other pockets of the carrier with one of said 95 seaming heads, seaming mechanism in each seaming head, means for operating said seaming mechanisms, and means for presenting cans and caps to said seaming mechanism in the sealing chambers successively.
15. In a can capping machine, the combination with a framework, a can and cap carrier having pockets, and two seaming heads 100 to coöperate with the pockets of the carrier to form sealing chambers and means for closing said sealing chambers, of two parallel elongated ports in the framework, exhausting pipes connected with the respective ports, alternate pockets of the carrier having ports to communicate with one of said 105 elongated ports, the other pockets of the carrier having ports to communicate with the other elongated port, seaming mechanism in each seaming head, means for operating 110
16. In a can capping machine, the combination with a framework, a can and cap carrier having pockets, and two seaming heads 115 to coöperate with the pockets of the carrier to form sealing chambers and means for closing said sealing chambers, of two parallel elongated ports in the framework, exhausting pipes connected with the respective ports, alternate pockets of the carrier having ports to communicate with one of said 120 elongated ports, the other pockets of the carrier having ports to communicate with the other elongated port, seaming mechanism in each seaming head, means for operating 125
17. In a can capping machine, the combination with a framework, a can and cap carrier having pockets, and two seaming heads 130 to coöperate with the pockets of the carrier to form sealing chambers and means for closing said sealing chambers, of two parallel elongated ports in the framework, exhausting pipes connected with the respective ports, alternate pockets of the carrier having ports to communicate with one of said elongated ports, the other pockets of the carrier having ports to communicate with the other elongated port, seaming mechanism in each seaming head, means for operating 130

ating and controlling said seaming mechanisms, and means for presenting each can and cap thereon to the two seaming mechanisms in the two vacuous chambers successively.

16. In a can capping machine, the combination with a rotary seaming roll carrier and a chuck, of levers mounted in said carrier, a seaming roll carried by each lever, 10 an adjustable stop carried by each lever to engage the chuck for limiting the movements of the seaming rolls toward the chuck,

springs connected with said levers to move the seaming rolls in a direction away from the chuck, a cone coöperating with said levers to control the operation of the seaming rolls, and means for actuating said cone.

In testimony whereof, I have signed this specification in the presence of two subscribing witnesses.

ADOLPH K. MALMQUIST.
